UNITED STATES PATENT OFFICE

2,218,687

DRINKING FOUNTAIN

Hoyt L. Spade, Robinson, Ill.

Application February 24, 1940, Serial No. 320,629

1 Claim. (Cl. 299—12)

This invention relates to drinking fountains especially adapted for pumps of wells, and has for the primary object the provision of an efficient and inexpensive device of this character which is of a valveless construction and may be easily and quickly installed on a pump, so that whenever the latter is operated in the usual manner by a person, water will flow from the fountain in proper amount for drinking and if the pump is operated slowly, the fountain will be sufficient to carry off the output of the pump. However, during a fast operation of the pump water will discharge from the fountain and the pump permitting the person to obtain water from the usual discharge of the pump if desired and further it is to be understood that the device being valveless will be self-draining as soon as the operation of the pump is discontinued thus preventing freezing in cold weather and consequently maintaining the device ready for use under all temperatures.

With these and other objects in view, the invention consists in certain novel features of construction, combination and arrangement of parts to be hereinafter more fully described and claimed.

For a complete understanding of my invention, reference is to be had to the following description and accompanying drawings, in which—

30 Figure 1 is a side elevation illustrating a drinking fountain constructed in accordance with my invention and showing the application thereof to a pump.

Figure 2 is a top plan view, partly in section, illustrating the same.

Figure 3 is a fragmentary vertical sectional view illustrating a portion of the drinking fountain and more particularly to the association of the nozzle with the basin or bowl of the fountain.

40 Figure 4 is a top plan view illustrating the nozzle.

Figure 5 is a top plan view illustrating the support and main water conduit of the fountain.

Figure 6 is a detail sectional view taken on the line 6—6 of Figure 1.

45 Referring in detail to the drawings, the numeral 5 indicates a conventional type of hand operated pump shown associated with a well covering 6 and includes the usual discharge neck 7. The pump 5 below the discharge neck 7 has drilled or otherwise formed therein a port 8. This port will permit water to escape from the pump below the neck 7 when the pump is operated and is provided in the latter for the purpose 50 of permitting a fountain 9 forming the subject

matter of the present invention to be installed on the pump.

A supporting arm 10 includes an angularly related end portion 11 and is provided with a bore 12 extending from end to end thereof. Integral 5 with one end of the supporting arm 10 is a concaved flange 13 having apertured ears 14. The concaved flange 13 fits the pump 5 about the port 8 and is held thereon by U-bolts 15 extending through the apertured ears 14 and receiving 10 nuts 16 thereon. A suitable gasket 17 is arranged between the flange 13 and the pump to prevent leakage. The other end of the supporting arm 10 has integral therewith an apertured 15 attaching flange 18.

A basin or bowl 19 is provided adjacent one end with a port 20 and the flange 18 is employed for securing the supporting arm onto the basin 19 with the bore 12 thereof in communication with the port 20.

20 A discharge nozzle 21 has a bore 22 which communicates with the port 20. The nozzle 21 is equipped with apertured flanges 23 through which fasteners may extend and also through the basin 19 and the apertured flange 18 for 25 firmly anchoring these parts onto the basin. Gaskets 24 are arranged between the nozzle and the basin and between the latter and the flange 18. The nozzle 21 includes a top inclined face 25 through which the bore 22 extends. The 30 portion of the bore 22 opening outwardly through the inclined face 25 is reduced in size over the remaining portion of the bore. Formed on the inclined face 25 and extending upwardly in an arcuate curvature is a deflector or guard 26 for 35 the purpose of shielding the inclined face 25 of the nozzle as well as the end of the bore 22 which opens through said inclined face.

The basin 19 adjacent the opposite end thereof is provided with a drain port 27 and a discharge 40 neck 28 having direct communication with the port 27 and forms an integral part of the bottom wall of the basin. A drain pipe 30 is threaded into the neck 28 and may include beveled sections, as shown in Figure 1, connected by a coupling 31 whereby the drain pipe may be made to extend downwardly and angularly to the basin 45 19 for the purpose of discharging the waste water into a drain trough 32. The drain trough 32 is of a conventional construction employed in connection with pump wells.

50 From the foregoing description it will be seen that a drinking fountain of this kind is extremely easy to install upon a conventional type of pump and in such a manner that the entire device will 55

be self-draining whenever the pump is not in operation. However, when the pump is operated by a person in the usual way water will discharge from the nozzle 21 in proper amount for 5 drinking permitting the person who is operating the pump to obtain the drinking water. Also it will be noted that the fountain will carry off the output from the pump when the latter is operated very slowly. However, a fast operation 10 of the pump will bring about discharge of water from the fountain as well as at the discharge neck 7 of the pump as usual so that a person can obtain water from the pump in a container or like device if desired.

15 It is believed that the foregoing description, when taken in connection with the drawings will fully set forth the construction and advantages of this invention to those skilled in the art to

which such a device relates, so that further detailed description will not be required.

Having thus described my invention, what I claim is:

In a valveless and self-draining drinking fountain for well pumps, a hollow supporting pipe having one end in direct communication with a restricted opening provided in a stand pipe of a pump below a main water outlet of said pump, means for detachably securing the supporting pipe on the stand pipe of the pump, a basin having a port connecting with said supporting pipe and detachably secured thereto, a drain for said basin, and a drinking nozzle in direct communication with the port of the basin and detachably secured to and located within the latter. 5 10 15
